UNITED STATES PATENT OFFICE.

ROBERT H. GRAY, OF LEXINGTON, KENTUCKY.

CONVEYER.

SPECIFICATION forming part of Letters Patent No. 727,127, dated May 5, 1903.

Application filed March 8, 1902. Renewed April 9, 1903. Serial No. 151,923. (No model.)

To all whom it may concern:

Be it known that I, ROBERT H. GRAY, a citizen of the United States, residing at Lexington, in the county of Fayette and State of Kentucky, have invented a new and useful 5 Conveyer, of which the following is a specification.

The present invention relates to conveyers, and while particularly intended for that class 10 of pumps employing an endless chain with a plurality of buckets thereon it will be evident that it may be used in many other relations.

One of the objects of the invention is to 15 provide a conveyer of this character in which the buckets or receptacles are so constructed that they can be located close together without interfering with each other, thereby forming a conveyer that will transport a comparatively 20 large amount of material and in case of use in a well will carry enough air into the water to keep it in thoroughly-aerated condition.

Another important object is to improve the 25 links and the means for attaching the buckets or receptacles thereto, so that the structure is greatly simplified, but at the same time is strong and not liable to become deranged, all of which will hereinafter more 30 fully appear.

In the accompanying sheet of drawings the preferred embodiment of the invention is clearly illustrated, and the construction and operation thereof are fully described in 35 the following specification.

It will of course be understood that such changes and modifications may be made from the construction set forth as fall within the scope of the claims hereto appended.

40 In the drawings, Figure 1 is a longitudinal section of the upper portion of a well-known form of water-elevator, showing the improved conveyer applied thereto. Fig. 2 is a perspective view, on an enlarged scale, of one of the links and buckets of said conveyer. Fig. 3 is a vertical sectional view through the same. Fig. 4 is a vertical sectional view taken on the line $\alpha\alpha$ of Fig. 3.

Similar numerals of reference indicate corresponding parts in all the figures of the drawings.

In carrying out the invention as shown

the chain or belt is made up of the plurality of links 10, pivotally connected by loops 11. On the side of each link there is secured a 55 receptacle or bucket 12, this receptacle being in the form of an inverted cone, preferably made of a single piece of sheet metal and having the inset portion 13 at the upper end of the rear wall to permit of the necessary 60 play of the contiguous loop 11 and the entrance of the tooth of the sprocket-wall therein. As will be seen by reference to Fig. 1, the closed end or apex of each receptacle is located within the open end of the one adjacent thereto, and because of these closed ends being contracted they will have sufficient play in the adjacent open ends, while at the same time they will not interfere with the discharge of the water. By this construction 65 it will be seen that the buckets are located close together, so that a comparatively large number can be placed upon the belt or chain, and a correspondingly large amount of water will be carried thereby.

75 Referring now to Figs. 2, 3, and 4, it will be seen that the links 10 comprise sheet-metal plates, the opposite ends of which are doubled, as at 14, thereby forming eyes 15, in which the loops 11 are pivotally mounted. 80 The receptacles or cups are located upon one side of the plates and are secured thereto by the attaching devices, (designated as a whole by the reference-numeral 16.) These attaching devices are each in the form of a wire, 85 one portion of which, as 17, is looped about the contracted end and passes through the adjacent doubled end 14 of the plate. From this point the two portions of the wire extend longitudinally of the plate to the opposite 90 doubled end, through which they pass, the terminals extending through the adjacent portion of the receptacle and being bent downwardly, as shown at 18. It will therefore be seen that this fastening device not 95 only serves as means for attaching the bucket to the plate, but also performs the function of holding the doubled terminals of said plate together, so that the loops cannot be pulled from their respective eyes. An exceedingly 100 simple device is therefore formed, in which a minimum number of parts are employed. The combination can thus be gotten up very inexpensively and at the same time will be

as strong and durable, if not more so, than the construction ordinarily employed.

From the foregoing it is thought that the construction, operation, and many advantages of the herein-described conveyer will be readily apparent to those skilled in the art without further description, and it will be understood that various changes in the form, proportion, and minor details of construction may be resorted to without departing from the principle or sacrificing any of the advantages of this invention.

What I claim, and desire to secure by Letters Patent, is—

1. In a conveyer of the class described, a link having a doubled end constituting an eye, a receptacle, and a fastening device for attaching the receptacle to the link, said fastening device passing through the doubled end and constituting holding means therefor.

2. In a conveyer of the class described, a link having its opposite ends doubled, forming terminal eyes, a loop pivoted in each eye, a receptacle located upon one side of the link, and a fastening device for securing the receptacle to the link, said device passing through the doubled ends of the link and engaging the receptacle contiguous to its opposite ends.

3. In a conveyer of the class described, a

link-plate, a receptacle located upon one side 30 of the plate and having an open end and a contracted closed end, and a fastening device looped about the closed end and passing through the plate, the terminals of said fastening device being secured to the open end 35 of the receptacle.

4. In a conveyer of the class described, a link-plate having its opposite ends doubled, forming terminal eyes, loops pivoted in each eye, a conical receptacle made of one piece 40 of sheet metal and located upon one side of the link-plate, and a fastening device for securing the receptacle to the plate, the same comprising a wire looped about the closed end of the receptacle and passing through 45 one doubled end of the plate, said wire extending longitudinally of the plate, passing through the other doubled end, and having its terminals secured to the adjacent portion of the receptacle.

In testimony that I claim the foregoing as my own I have hereto affixed my signature in the presence of two witnesses.

ROBERT H. GRAY.
